(57) **CLAIM**

The ornamental design for the digital voltage indicator, as shown and described.

DESCRIPTION

FIG. 1 is a perspective view of the digital voltage indicator showing my new design;

FIG. 2 is a front elevational view thereof;

FIG. 3 is a rear elevational view thereof;

FIG. 4 is a side elevational view of the one side thereof;

FIG. 5 is a side elevational view of the other side thereof;

FIG. 6 is a top plan view thereof; and,

FIG. 7 is a bottom plan view thereof.
